UNITED STATES PATENT OFFICE.

VINCENT H. BENDIX, OF NEW YORK, N. Y.

DESIGN FOR A REAR FRAME FOR MOTOR-CYCLES.

SPECIFICATION forming part of Design No. 34,902, dated August 6, 1901.

Application filed July 6, 1901. Serial No. 67,371. Term of patent 7 years.

To all whom it may concern:

Be it known that I, VINCENT H. BENDIX, a citizen of the United States, residing in the borough of the Bronx, New York city, State of New York, have invented and produced a new and original Design for Rear Frames of Motor-Cycles, of which the following is a specification, reference being had to the accompanying drawing, forming part thereof.

The figure is a perspective view showing my new design.

As shown in the drawing, the leading or material feature of my design consists in a rear frame divided into a front or motor section, and a rear or wheel section by a cross-bar *a*, substantially parallel with the bar or post *b*, the lower end of bar *a* being curved to form a motor-support *c* and extended from the

curve to the bracket *d* on a line substantially parallel with the bottom bars *e e*. The bar *f* extends from the upper end of bar *a* to the bar or post *b* on a line substantially parallel to and in continuation of the top bars *g g*.

Having described my invention, what I claim as new, and desire to secure by Letters Patent, is—

The design for a rear frame of a motor-cycle, as herein shown and described.

In testimony whereof I have signed my name to this specification in the presence of two subscribing witnesses.

VINCENT H. BENDIX.

Witnesses:

GEO. V. SMITH,
SEABURY C. MASTICK.
